UNITED STATES PATENT OFFICE.

ALBERT H. MCALLISTER, OF NEW ALBANY, MISSISSIPPI, ASSIGNOR TO THE MCALLISTER MACHINE GUN COMPANY, OF MEMPHIS, TENNESSEE.

MACHINE-GUN.

SPECIFICATION forming part of Letters Patent No. 674,811, dated May 21, 1901.

Application filed December 12, 1898. Serial No. 699,009. (No model.)

To all whom it may concern:

Be it known that I, ALBERT H. MCALLISTER, a citizen of the United States, residing at New Albany, in the county of Union and State of Mississippi, have invented certain new and useful Improvements in Machine-Guns; and I do hereby declare the following to be a full, clear, and exact description of the invention, such as will enable others skilled in the art to which it appertains to make and use the same.

This invention relates particularly to machine-guns intended for use upon fortifications or ships or in situations where they may be mounted on fixed carriages or supports. The gun substantially unchanged may, however, be mounted on a wheeled carriage for use in the field. The object is to provide a simple and serviceable gun that shall combine a maximum of destructive effect with a minimum of complication and cost.

The gun consists generally of one or more horizontal rows of normally parallel barrels, a plane firing-plate provided with corresponding rows of perforations to serve as cartridge-chambers and arranged to advance step by step across the rear ends of the barrels to bring the rows of chambers successively into alignment with the barrels, means for inserting cartridges in each row of chambers before it reaches such alignment, means for firing the cartridges when in such alignment, and means for ejecting the shells after they have passed the firing-point.

In the drawings, Figure 1 is a plan view of the gun. Fig. 2 is a side elevation. Fig. 3 is a front elevation. Fig. 4 is a central vertical section parallel to the line of fire; Fig. 5, a rear view showing certain shipping devices. Fig. 6 is a detail of certain locking mechanism. Figs. 7 and 8 are respectively plan and vertical sections of a part of a block supporting the magazine. Fig. 9 is a detail view of devices for disconnecting certain loading devices. Fig. 10 is a detail plan of firing mechanism. Fig. 11 shows optional means for counterweighting the firing-plate. Fig. 12 shows a slight detail modification.

The working parts of the machine are all supported by a heavy base A. Above this bed is a horizontal base-plate A', which is supported by balls A", held in place by a

boss A³ and bolt A⁴ and turned in its own plane by means of a hand-operated worm A⁵, supported from the bed and engaging a central worm-gear A⁶, fixed to the base-plate. 55 From opposite sides of the base-plate rise posts B B, and these support a rigid frame consisting of two heavy uprights B' B', horizontal members B² B², and braces B³ B³. Between the longer horizontal members B² is fixed a breech-block C, and in this are inserted the rear ends of two parallel horizontal rows of barrels C', each barrel end in the lower row being vertically below the corresponding one in the upper row. The muzzle portions 60 of the barrels are supported by the front frame member B², which is slotted from end to end, so that a lower part supports the lower barrels directly, an upper part rests upon the upper barrels, and a middle part lies between the two sets. These front portions of the barrels are separated by wedges C², each perforated near its upper end to pass over a shaft C³, eccentrically mounted in bearings on the frame B² and rotated by hand-levers C⁴. The 65 wedges project below the lower set of barrels and are prevented from rotating with the shaft by means of bars C⁵, fixed to the opposite sides B² of the frame. The barrels are virtually pivoted near their rear ends by giving the 70 breech-block openings a width gradually increasing in passing from the pivotal point. Rotation of the eccentric-shaft C³ depresses the wedges and forces the barrels to diverge slightly. Springs C⁶ press the outer barrels of 75 each row inward and when the shaft is rotated in a contrary direction first return all to normal position and then force all to converge slightly. By this means the whole series of 80 balls delivered by one row of barrels at one 85 discharge may be made to have any desired uniform spacing when they reach any given distance from the machine—for example, with eighteen barrels in each row, as in the gun 90 from which the drawings were made, at four 95 hundred yards they may be one foot apart, with extreme right and left balls seventeen feet apart. On the other hand, if it be desired to make a breach in anything penetrable or seriously affected by projectiles of the 100 size used the whole series may be made to strike within an extremely narrow space.

The elevation of the barrels may be changed through any desired angle by rotating a shaft C⁷, mounted upon the base-plate and provided with two eccentrics C⁸, working in the usual straps and supporting struts C⁹, pivotally connected at C¹⁰ with a cross-bar C¹¹ of the frame.

To the members B' B², upon opposite sides of the machine, are rigidly fixed uprights B⁴, grooved upon their inner sides to form ways for a thick firing-plate D, which slides vertically in close proximity to the breech-block C, and the rear ends of the barrels mounted therein. The firing-plate is provided with sets of perforations, each set adapted to register with the set of barrels. The plate is raised to stops D', at the upper limit of its path, by means of duplicate mechanisms on each side of the machine, consisting of crank-wheels E, gears F⁰ G' upon the same shaft F^X, shafts F¹, gears F², shaft F³, and a pinion F⁴ engaging vertical racks F⁵, rigidly fixed to the firing-plate D near its edges and projecting both above and below the same, as is clearly seen in Fig. 4. The plate being raised to the top of the upper end of the way is lowered by steps, such as to bring each set of its perforations in turn into alinement with the barrels, and this lowering is brought about by continuing the rotation of the wheels E, by which it was raised, a lever G being first swung to throw the gears F⁰ out of engagement and mutilated gears G' into engagement with the gears F. The lever acts through links G², bars G³, and shippers G⁴ to produce this change of engagement, and when the change has been made the mutilated gears lower the plate D one step and then through mutilation cease to act, while the wheels E complete the revolution, the rotation of the shafts F' being meantime prevented by spring-pressed pawls H, Figs. 2, 4, and 6, which engage ratchet-teeth H' upon collars rigidly fixed to the shafts.

At the completion of the revolution of the wheels E the mutilated gears reengage, and at the same instant the pawls are struck by projections H² upon the wheels and forced to release the shafts, when the firing-plate is lowered another step, as before, and so on until it has again reached its lowest point.

When the firing-plate is at its upper limit of movement, its lowest set of perforations is one step above alinement with the barrels, and when it is at its opposite limit its upper set is one step below such alinement. While it is momentarily at rest at its upper limit cartridges are forced into the perforations of its lower set by plungers I, sliding forward in suitable passages J in a fixed block J'. The plungers are advanced at proper intervals by the rotation of the shaft F^X, which by means of suitably-mutilated gears I⁰ rotates a shaft I', while the mutilated gears G' are inactive. This latter shaft bears eccentrics I², and these acting through rods I³, pivoted levers I⁴, and links I⁵ drive forward the

plunger-carrying head I⁶, which slides in suitable ways I', supported from a bar B^X, attached to the frame members B². The cartridges are fed to the plungers from a magazine K, which at the bottom is flanged to engage flanges upon the block in which the plungers work and is removably held above by spring-catches K', engaging studs upon its sides. The magazine is cylindrically curved, closed below until in place by removable slides K⁰, which are removed by hand, and divided into small transverse cells extending from top to bottom and each adapted to receive superposed cartridges. Upon the rear face is a horizontal bar K², borne by arms K³ at its ends, pivoted to the frame of the machine at K⁴ in the axis of curvature of the magazine and constantly urged toward the bottom of the magazine by springs K⁵. From the bar fingers K⁶ project into the magazine-cells, respectively, through slots K⁷, that extend from top to bottom of its rear face. The bar being raised above the magazine, the latter may be removed and replaced by another, and this done the arm is allowed to descend, so that its fingers rest upon the upper cartridges and so press all downward toward the paths of the plungers. The plunger-passages in the block are upwardly open beneath the magazine, alternate slots bending to one side, as shown in Fig. 8, to reach the lower chambers in the block. The plate having descended one step after a set of cartridges has been fired, the shells of that set are ejected and the chambers are cleaned by brush-bearing ejector-rods L, fixed in a cross-head L', moving in ways on the frame and actuated by rods L², attached to the lower ends of the levers I⁴, which actuate the loading-plungers. That all the sets of cartridges may be fired it is necessary that the firing-plate should pass below the loading-plungers, and obviously the latter should not operate during the time when no cartridges can be inserted. They are thrown out of action at proper times by strips M, Fig. 9, which are fixed to the firing-plate and its racks in position to strike the end of a centrally-pivoted lever M', whose opposite arm lies beneath the link I⁵ and lifts its slotted front end out of engagement with the plunger-carrying bar I⁶.

As the cartridges of each set rest momentarily in alinement with the barrels, they are fired by firing-pins N, set in a head N' and working through a bar N², rigidly supported from the frame of the machine. The head is retracted by cams N³, fixed upon the shaft F^X, and working in stirrups at the ends of jointed rods N⁴, which are attached to the head. Once in each rotation these cams retract the head and then suddenly release it. When thus released, it is shot forward by springs N⁵, reacting against an adjustable thimble N⁶ in a cross-bar of the frame. To the head N' are attached besides the rods N⁴ jointed rods N⁷, which terminate in loops N⁸, passing around

an eccentrically-mounted shaft N⁹. This shaft is rotated by a hand-lever N¹⁰, provided with the usual pawl to engage a quadrant N¹¹. By swinging this lever the head N' may 5 be so far retracted that the cams N⁸ have no retracting action, and hence the firing-pins remain stationary, for example, while the plate is being raised.

Upon the frame, at the front and rear, respectively, are supported two light bars U U' 10 to serve as sights.

The plate A' may, if desired, be rigidly locked to the base by a screw W, Figs. 2 and 3, operated by a lever W'.

15 The firing-plate D is necessarily somewhat heavy, and, if desired, it may be counterweighted. Fig. 11 shows, diagrammatically, a means to this end, cords V being attached to the plate and passing over pulleys V' to a 20 weight V².

It may in some cases be desirable to have the ball portion of the cartridge entered into the barrel before firing, and in Fig. 12 I illustrate a construction for this purpose. The 25 firing-pin is a short projection on a rod X, large enough to nearly cover the end of the cartridge. Upon this is a sleeve Y, normally held in advance of the firing-pin by a spring Y'. The firing-plate is recessed, so that this 30 sleeve may first strike the outer edge of the cartridge end and force it forward. When it can go no farther, the sleeve yields and the firing-pin acts in the usual way. No means for locking the firing-pin bar is here shown.

35 I do not limit myself to the exact constructions, but wish to cover my invention broadly as well as specifically.

What I claim is—

1. The combination with a set of barrels, 40 of a plane firing-plate moving step by step in a transverse path across their rear ends and provided with sets of perforations each corresponding with the set of barrels, loading mechanism above the plane of the barrels, firing mechanism in the plane of the barrels, ejecting mechanism below the plane of the barrels, means for bringing the last set of perforations into alinement with the loading mechanism, and means for advancing the 45 plate step by step until its first set of perforations alines with the ejecting mechanism.

50 2. The combination with a set of barrels secured in an approximately horizontal plane, of a firing-plate mounted to slide perpendicularly with reference to that plane and provided with sets of cartridge-bearing perforations, means for lowering the plate by successive steps to bring the sets of perforations one after another into alinement with the barrels, means for loading the sets in succession, means for firing cartridges in such alined perforations, a corresponding set of shell-ejectors, a single operating device connected with the plate-moving, firing and ejecting devices 55 to operate automatically all in proper sequence.

3. The combination with the bed and the

base-plate, of the gun-carrying frame supported therefrom, the shaft mounted upon the base-plate, the eccentrics thereon, and 70 the struts supported by said eccentrics and pivotally connected to the frame above.

4. The combination with a set of barrels in a plane, of a set of transverse wedges lying near the muzzles in the spaces between the barrels, respectively, an eccentric-shaft arranged to advance and retract all the wedges simultaneously by its rotation, means for rotating the shaft, and springs offering yielding resistance to the separation of the barrels. 75 80

5. The combination with a set of normally horizontal barrels mounted in the same plane, of a counterweight firing-plate arranged to slide vertically across the rear ends of the barrels and provided with sets of perforations 85 each set adapted to register with the set of barrels, means for lowering the plate step by step to bring the sets of perforations successively into such registry, means for automatically loading each set of perforations before it 90 reaches such registering position, means for automatically firing the cartridges of each set while so registering, and means for automatically ejecting the shells of each set after they pass below the barrels. 95

6. The combination with a firing-plate having numerous sets of perforations, of a rotary shaft, gearing operated by the rotation of the shaft to lower the plate step by step and bring said sets successively to the same position, a 100 corresponding set of ejectors alining with said sets when in such position, and means whereby the rotation of the shaft advances and retracts the ejectors.

7. The combination with a firing-plate arranged to move step by step in one direction and provided with many sets of cartridge-receiving perforations, of a corresponding set of loading-plungers arranged to aline successively with the sets as they advance, a corresponding set of firing-pins arranged to aline temporarily with each loaded set of perforations after it has passed the plungers, a corresponding set of ejectors arranged to aline with the sets in succession after they pass 110 the firing-pins, and means whereby the plungers, pins and ejectors are all automatically actuated once during the interval between successive steps of the firing-plate. 115

8. The combination with a vertically-sliding firing-plate provided with numerous sets of perforations, of means for raising the plate, means for lowering it step by step, loading, firing and ejecting devices arranged in proximity to the path of the plate and in position 120 to aline at the same time with different sets of said perforations, and automatic means whereby all said devices are actuated in proper order during the rests of the plate. 125

9. The combination with a sliding firing-plate having several sets of perforations, of automatically-operated loading, firing and ejecting devices arranged in sequence along 130 side its path, means for sliding the plate to

bring one terminal set of perforations into alignment with the loading devices, and means for advancing it step by step in the opposite direction until the opposite terminal set registers with the ejecting devices.

10. The combination with a movable firing-plate having several sets of perforations, of means for moving the plate step by step in one direction, automatically-acting loading, 10 firing and ejecting devices arranged in succession alongside the path of the plate, means for operating each during the rests of the plate, and automatic means for preventing the action of the loading devices after the last 15 set of perforations has passed.

11. The combination with the firing-plate arranged to slide in ways and provided with rack-teeth at its lateral margins, gears engaging the racks, respectively, a power-shaft 20 and means whereby the rotation of the power-shaft in the same direction may rotate said gears positively in either direction at will.

12. The combination with a set of barrels 25 and a sliding firing-plate contiguous to their rear faces, means for inserting sets of cartridges in the firing-plate, automatic means for advancing the plate to bring the sets of cartridges in line with the barrels, automatic means for entering each cartridge in its barrel, and automatic means for then exploding 30 the entered cartridges.

13. The combination with a firing-plate, of a rotary shaft, loading, firing and ejecting devices all automatically operated by the rotation of the shaft, and means whereby the 35 firing-pin may at will be thrown out of action.

without affecting the operation of the other devices.

14. The combination with a set of barrels and a firing-plate mounted to slide vertically over their rear end faces, gearing engaging said plate to raise and lower it, an actuating-shaft provided with a mutilated and a non-mutilated gear, and means for at will throwing either into engagement with said gearing, 45 whereby the plate may be moved either continuously or step by step as said shaft rotates.

15. The combination with a set of barrels and a firing-plate mounted to move across their rear end faces, of plate-loading devices, 50 cartridge-firing devices, shell-ejecting devices, an actuating-shaft, gears mounted on said shaft and connected to the firing-plate to actuate it, and cams fixed upon said shaft 55 and actuating in proper succession the loading, firing and ejecting devices.

16. The combination with a firing-plate having sets of cartridge-chambers, of means for moving the firing-plate step by step, a set of loading-plungers on one side of the firing-plate's path, a set of ejectors upon the opposite side of said path but at a more advanced point thereof, and a single means for moving the plungers and ejectors simultaneously in 60 opposite directions. 65

In testimony whereof I affix my signature in presence of two witnesses.

ALBERT H. MCALLISTER.
